UNITED STATES PATENT OFFICE.

WILLIAM E. MATTHEW, OF BUCYRUS, OHIO.

TORPEDO.

No. 825,229.

Specification of Letters Patent.

Patented July 3, 1906.

Application filed October 13, 1905. Serial No. 282,685.

To all whom it may concern:

Be it known that I, WILLIAM E. MATTHEW, a citizen of the United States, residing at Bucyrus, in the county of Crawford and State of Ohio, have invented certain new and useful Improvements in Torpedoes; and I do hereby declare the following to be a full, clear, and exact description of the invention, such as will enable others skilled in the art to which it appertains to make and use the same.

My invention relates to torpedoes of that character utilized by railroads for signal purposes; and its object is to provide a torpedo which is formed entirely of paper, which is of simple construction, and which does not require the use of any special means for securing the fastening-strip to the torpedo.

The invention consists of a substantially flat tubular envelop having its ends slit, so that the same can be caused to interlock, and within these slits is disposed a fastening-strip adapted to be placed in engagement with a rail. The ends of the envelop are adapted to be permanently secured by a suitable adhesive material, so that displacement of the parts will not occur.

The invention also consists of certain other novel features of construction and combination of parts which will be hereinafter more fully described, and pointed out in the claims.

In the accompanying drawings I have shown the preferred form of my invention.

In said drawings, Figure 1 is a perspective view of my improved railway-torpedo. Fig. 2 is a longitudinal section therethrough, and Fig. 3 is a detail view of the envelop.

Referring to the figures by numerals of reference, 1 is a substantially flat tubular envelop formed of paper or other fibrous material, and oppositely-disposed slits 2 are formed within each end of the tube, so as to produce tongues 3 and 4 at opposite ends of the envelop, respectively. The tongues 4 are rounded and narrower than the tongues 3, so that the same may be readily inserted between said tongues 3 when the torpedo is folded.

In using the torpedo herein described the envelop is folded upon itself at about the point indicated by dotted line 5 in Fig. 3, and the tongue 3, contacting with said envelop, is then fastened in place by means of a strong glue. A quantity of explosive material 6 is then placed within the envelop, and the tongues 4 and the adjoining portion of the

envelop are folded back on the dotted line 7 shown in Fig. 3. A fastening-strip 8, of soft metal, is then inserted between the tongues 4, and said tongues are fastened together at their ends by glue, and their outer faces are then also covered with adhesive material, after which said tongues 4 are inserted between the tongues 3 until the strip 8 contained therebetween comes into contact with the ends of the slits formed between said tongues 3. All four tongues will then be held permanently fastened by the glue thereon, and the fastening-strip 8 will be securely maintained in proper position. The explosive contents of the torpedo are fully protected from moisture, because it becomes unnecessary with this arrangement to perforate the envelop. Moreover, no particular means other than glue are necessary for fastening the torpedo together after the same has been filled, and as a result an all-paper torpedo is formed.

Having thus fully described my invention, what I claim as new, and desire to secure by Letters Patent, is—

1. A torpedo formed of a tubular envelop having integral tongues at its ends, said envelop having its ends folded upon itself and its tongues interlocking and secured together, and a fastening-strip interposed between and retained by the tongues.

2. A torpedo comprising a tubular envelop open at its ends and having integral tongues at said ends, said envelop having its ends folded upon itself and the tongues of one end 90 extending between the tongues of the other end, all of said tongues being permanently fastened together by an adhesive material, and a fastening-strip extending between and retained by the tongues.

3. An all-paper torpedo comprising a substantially flat tubular envelop having a pair of tongues at each end, the tongues of one end being narrower than the remaining tongues, the ends of the envelop adapted to fold inward and the tongues to interlock, the narrow tongues projecting into one end of the envelop when the same is folded, said tongues being held together by an adhesive material, and means extending between and retained by the tongues for securing the torpedo to a rail.

4. A torpedo comprising a substantially flat tubular envelop having a pair of tongues at each end, an explosive material within the

central portion of the envelop, the end portions of the envelop extending over the central portion thereof and having their tongues interlocking and secured by an adhesive material, and means extending between and retained by the tongues for fastening the torpedo to a rail.

In testimony whereof I have signed my name to this specification in the presence of two subscribing witnesses.

WILLIAM E. MATTHEW.
